BERT G. DUNHAM, OF HAWTHORNE, NEW JERSEY, ASSIGNOR, BY MESNE ASSIGNMENTS,
TO WESTERN ELECTRIC COMPANY, INCORPORATED, A CORPORATION OF NEW YORK.

TELEPHONE-EXCHANGE SYSTEM.

1,262,315.

Specification of Letters Patent. Patented Apr. 9, 1918.

Application filed October 5, 1915. Serial No. 54,148.

To all whom it may concern:

Be it known that I, BERT G. DUNHAM, a citizen of the United States, residing at Hawthorne, in the county of Passaic and 5 State of New Jersey, have invented certain new and useful Improvements in Telephone-Exchange Systems, of which the following is a full, clear, concise, and exact description.

This invention relates to telephone exchange systems and has to do more particularly with a test or control circuit for telephone exchange systems utilizing automatic switches to extend the desired connection. The object of the invention is to provide 15 effective and simplified means associated with the lines and switches for testing the lines at a single test contact on each switch for each line.

In automatic switches of the character referred to, there is usually a circuit known as a "test circuit" thereof, including a test brush on the movable portion of such switch which tests on the one hand the calling or non-calling condition of the line, or, on the 25 other hand, the busy or idle condition of the line, depending upon whether such automatic switch is a line finder switch or a connector switch.

According to one feature of the invention, 30 a source of current is normally connected, through the line cut-off relay of each subscriber's line, to multiply connected calling and called test terminals thereof, adapted to cause energization of the cut-off relay upon selection of the line by either a line 35 finder or a connector switch over a circuit including any one of said test terminals.

Another feature of the invention resides in the means for decreasing the resistance of 40 the test circuit of each subscriber's line whereby, responsive to a call over any one of the subscriber's lines, the potential of the test terminals of such line is increased sufficiently to render the line selectable by the 45 line finders.

Another feature of the invention resides in the means employed for energizing the cut-off relays of the lines responsive to their selection by the line finders, together 50 with the means employed for simultaneously therewith rendering a selected line unselectable by either a line finder or a connector.

Other novel and useful features of the invention will more fully appear from the

following detailed description and appended 55 claims.

Referring now to the drawing, for the purpose of simplifying the disclosure a plurality of battery symbols are illustrated. It is to be understood, however, that a single 60 battery only need be employed. Therefore, it is to be assumed that each battery symbol represents one and the same battery, and will be designated in the description following as battery B. For the purpose of 65 still further simplifying the disclosure, the circuits necessary to illustrate the invention only are shown, which includes a substation C, of a well-known arrangement, connected with its line circuit D which is located at the 70 central office, circuits of a line finder E and circuits of certain portions of a connector F.

The substation telephone lines 6 and 7 are divided into groups of 100 lines, each 75 terminating at the central office in a line circuit D which includes a line relay LR, a cut-off relay CO, and a resistance coil 11. For each group of 100 lines there is provided a plurality of line finders E, each having 100 sets of bank contacts or line terminals 8, 9, 80 10, each line being multiply connected to its terminal sets 8, 9, 10 of the associated line finders. These 100 sets of contacts are further divided into ten subgroups of ten contact sets each, so that in the operation of the 85 switch E the sets of its brushes 18, 19, 20 are first operated to the position corresponding to the subgroup of contacts containing the terminals of a calling line, and thereafter operated to cause the set of brushes, 90 corresponding to the selected subgroup, to select the desired terminals of the selected subgroup.

In order to control the selection of the 95 group of terminals containing the terminals of a calling line, each line finder is provided with a set of group contact terminals 21 and a co-operating brush 22, there being as many group contacts 21 as there are subgroups of sets of contacts 8, 9, 10, of which, 100 of course, there are ten. Therefore, it will be seen that each group of 100 lines is further divided into ten subgroups of ten lines each. For each subgroup of ten lines a group relay GBC is provided, being common 105 to its tens line circuits D and connected by a conductor 25 to its corresponding group test contact 21.

In like manner, each line of each group of 100 lines, as called lines, terminates in a set of passive contacts 111, 112, 113 of each of a plurality of connector switches, which are 5 divided, as in the line finders, into ten subgroups of ten sets each of contacts 111, 112, 113. Each of the connector switches is provided with a set of coöperating brushes for each subgroup, adapted to be rotated to the 10 position with the corresponding set of brushes in the position to be thereafter rotated into and out of connection with the terminals 111, 112, 113 of the selected subgroup to engagement with the set of terminals of a desired line.

The type of line finder and connector switches of the circuits illustrated are provided with a set of three brushes for each subgroup of terminals spirally arranged 20 upon a carrier (not shown) adapted to be rotated step by step, responsive to energizations and deenergizations of a herein termed rotary magnet, to the position corresponding to the subgroup in which a set of terminals 25 of a desired line is included, and thereafter the set of brushes, corresponding to the subgroup of the desired line, is rotated step by step, responsive to energizations and deenergizations of a herein termed vertical magnet, into and out of connection with the sets 30 of contact terminals of the lines of the selected subgroups until the set connected with the desired line is engaged. Thereafter, at the time of disconnection, the 35 brushes are restored to their normal position, responsive to the energization of a release magnet associated with and individual to each of the switches. In addition, each switch is also provided with what is commonly termed a side switch, which comprises 40 a plurality of brushes each adapted to be positioned to connection successively with a plurality of associated passive contacts. The side switch of each of the line finders 45 is provided with five brushes, each adapted to be adjusted successively to positions 1, 2 and 3 into engagement with passive contacts corresponding thereto.

Considering now the operation of the 50 illustrated arrangement, subscriber at substation C, desiring to initiate a call, removes the receiver from the switchhook, establishing an energizing circuit for line relay LR from grounded battery B, left-hand winding 55 of relay LR, outer contact of cut-off relay CO, line conductor 6, through the substation, returning over the line conductor 7, inner contact of relay CO, right-hand winding of relay LR to ground, which energizes 60 the relay LR, establishing circuit for the corresponding group relay GBC from ground, winding of GBC, contact of relay LR, winding of resistance coil 11, battery B to ground, and in multiple therewith 65 through winding of CO, battery B to

ground. CO is not energized, due to the resistance of the relay GBC in series. Also the connection of the winding of resistance coil 11 and battery B in multiple with the winding of the cut-off relay CO increases 70 the potential of the test contact 8 upon connection therewith of the brush 20 of the line finder.

The energization of relay GBC establishes circuit for the side switch magnet SSM from 75 ground, alternate contact of GBC, side switch arm 16, its engaged normal contact, normal contact 21, brush 22 in engagement therewith, left-hand contact of test relay TR, winding of side switch magnet SSM, 80 battery B to ground, and in multiple therewith circuit for the slow release control relays 23 of each of the line finders of the group from ground, alternate contact of GBC, contact or release magnet REL, winding of slow release relay 23, battery B to 85 ground, which energizes the magnet SSM and relays 23, establishing circuit for the flow of current from conductor 24, grounded at the first selector switch (not shown), 90 alternate contact of 23, contact of SSM, right-hand contact of TR, interrupter contact of rotary magnet RM, interrupter contact of vertical magnet VM, side switch arm 17, its engaged normal contact, winding of 95 RM, battery B to ground, which energizes the magnet RM, causing the brushes 18 to 20, inclusive, corresponding to each subgroup, to be moved one step in their primary direction and the brush 22 from connection 100 with its normal contact 21 to connection with its first contact 21 from normal. Whereupon circuit for the magnet SSM over the path including the normal contact 21 is interrupted and a substitute circuit, 105 unless the line of the calling substation be included in the subgroup corresponding to the first contact 21 from normal, established from ground, normal contact of relay GBC of the subgroup corresponding to the first 110 contact 21 from normal, thence over common conductor 25 to first contact 21 from normal, brush 22 now in engagement therewith, left-hand contact of TR, winding of SSM, battery B to ground, which holds magnet SSM 115 in its energized position and maintains the traced vibratory circuit for the magnet RM, which is again energized and the sets of brushes 18 to 20 inclusive rotated to the position corresponding to the second subgroup, 120 and the brush 22 to connection with the second contact 21, from normal, whereupon a substitute circuit for the magnet SSM is, unless the line of the calling substation be included in the second subgroup, 125 established, which includes normal contact of the relay GBC of the subgroup, second contact 21 from normal, and so on until the brush 22 engages contact 21 corresponding to a subgroup in which is included the line 130

of a calling substation awaiting selection, when, owing to the then energized condition of the corresponding relay GBC, circuit for the magnet SSM is interrupted and the magnet 5 deenergized, interrupting circuit for the magnet RM, thereby preventing its further energization.

Assuming the line of the substation C to be included in the subgroup corresponding 10 to the first contact 21 from normal, then, upon disconnection of the brush 22 from its normal contact, owing to the energized condition of the corresponding relay GBC, circuit for the magnet SSM is interrupted, the magnet 15 deenergized, which, by the opening of its contact, interrupts circuit for the magnet RM, preventing further rotation of the brushes, whereby the set of brushes 18 to 20, inclusive, corresponding to the first subgroup, are left in position to be moved into 20 connection with the set of contacts 8 to 10, inclusive, of the lines of the first subgroup. The deenergization of magnet SSM causes the rotation of the side switch brushes 13 to 25 17, inclusive, from connection with their associated normal contacts to connection with their associated first contacts from normal, which, by the interruption of brush 17 from its normal contact, disconnects magnet RM, 30 and by the connection of brushes 15 and 16 with their first contacts from normal connects the winding of relay TR with the brushes 20 and establishes circuit for the magnet SSM from ground, alternate contact of relay 35 GBC, brush 16, its engaged first contact from normal, left-hand contact of TR, winding of SSM, battery B to ground, which energizes the magnet SSM and establishes a vibratory circuit for the magnet VM from 40 conductor 24, grounded at the first selector switch, alternate contact of relay 23, contact of SSM, right-hand contact of TR, interrupter contact of RM, interrupter contact of VM, brush 17, its engaged first contact 45 from normal, winding of VM, battery B to ground, which energizes and moves the brushes 18 to 20, inclusive, corresponding to the selected subgroup, into engagement with the first set of contacts 8, 9, 10, multiply connected terminals of the first line of 50 the selected subgroup; whereupon, if such line be a calling line and awaiting selection, circuit for the flow of current sufficient to energize the relay TR is established from ground, winding of TR, first side switch contact from normal, brush 15 in engagement therewith, brush 20, engaged passive contact 8, winding of relay CO, battery B to ground, and in multiple therewith 55 through upper contact of relay LR, winding of coil 11, battery B to ground, which, by the opening of the contacts of TR, interrupts circuit for the magnet SSM which deenergizes and causes side switch brushes 13 60 to 17, inclusive, to be moved from connec- 65

tion with their first associated contacts from normal to connection with their second and last associated contacts from normal.

Assuming the line calling to be connected with a set of contacts 8 to 10, inclusive, other than the first set, then, owing to the absence of the connection of the winding of coil 11 and battery B therethrough with the contact 8 of such line, the flow of current through the relay TR will not be sufficient to cause its actuation, with the result that the magnet SSM remains energized and maintains the vibratory circuit for the magnet VM, which continues to be energized and deenergized until the brush 20 engages the contact 8 connected with a line awaiting selection, when, owing to the energized condition of the relay LR and the connection of the winding of resistance 11 and battery B with the contact 8 of such line, in multiple with the winding of CO, sufficient current flows through winding of relays TR and CO to cause their actuation, whereupon, by the opening of the contacts of TR, circuit for the magnet SSM is interrupted, the magnet 90 deenergized, interrupting circuit for the magnet VM, preventing its further energization, leaving the brushes 18 to 20, inclusive, in connection with their associated set of contacts 8 to 10, terminals of a calling line.

The deenergization of magnet SSM causes the side switch brushes 13 to 17, inclusive to be rotated from connection with their associated first contacts from normal to connection with their associated second and last contacts from normal. The disconnection of brush 15 from its second contact from normal interrupts the traced circuit for the relay TR, which deenergizes. The closure of the brush 15 with its second contact from normal establishes a maintaining circuit for the relay CO from ground, second contact from normal, brush 15 in engagement therewith, brush 20, engaged contact 8, winding of CO, battery B to ground, which, by the opening of its contacts, interrupts the circuit therethrough for the relay LR, which deenergizes, interrupting, by the opening of its contacts, circuit for the relay 100 GBC, which deenergizes opening its alternate contact, interrupting the starting circuit for the line finders and interrupting circuit for the slow-release relays 23, which deenergize. The connection of brushes 13 110 and 14 with their associated second contacts from normal extends the line of the calling substation to connection with the first selector, whereupon a relay (not shown) is brought into connection with the line and energized, which acts to disconnect ground from the conductor 24 to prevent the establishment of the energizing circuit for the release magnet REL following the deenergization of the slow-release relay 23. 115 120 125 130

Responsive to the connection of brush 15 with its second contact from normal, ground is connected with the multiply connected passive contacts 111 of each of the connector switches to the passive contacts of which are connected called terminals of the line, with the result that should selection of the line by any such connector switch be attempted, circuit will be established for the test relay 126 of such connector from grounded second side switch contact from normal, brush 15 in engagement therewith, brush 20, engaged passive contact 8, passive contact 111, brush 127, side switch arm 128, its associated first contact from normal, left-hand winding of test relay 126, battery B to ground, which will energize the relay and thereby, in a manner (not shown) prevent the selection of the line by such connector switch.

Following the extension of the line of the calling substation to the first selector, the subscriber, by operating the impulse transmitter thereat, may cause the actuation of the first selector to select an idle trunk of a desired group leading to and terminating in a second selector switch or connect or switch, and thereafter, by subsequent actuations of the impulse transmitter, cause the operation of such selected second selector or connector to select the called terminals 111, 112, 113 of a desired called substation. At time of disconnection, the conductor 24 is, in a manner not shown, connected with ground, and circuit established for the release relay REL which may be traced from grounded conductor 24, normal contact of relay 23, off-normal contact ON (closed, responsive to the first energization of magnet RM), winding of REL, battery B to ground, which energizes and restores the switch to its normal position. The disconnection of brush 15 from its second contact from normal or the disconnection of brush 20 from the contact 8, interrupts circuit for the relay CO which deenergizes and, by the closure of its contacts, re-establishes connection of the line relay LR with the line, whereby another call may be initiated over the line. Also, by the disconnection of brush 15 from its second contact from normal, ground is disconnected from the test terminals of the line, whereby the line is rendered selectable by the connectors. When the brushes of the line finder reach normal position, the contact ON is opened, which interrupts circuit for the release magnet REL. The connection of brush 16 with its normal contact, when brush 22 reaches normal position, places the line finder in position to be again actuated responsive to the next succeeding call.

What is claimed is:

1. In a telephone system, a subscriber's line, comprising a test terminal, a relay and a source of current connected with said terminal, a selector switch comprising a con-

trol relay, means responsive to initiation of a call over said line for decreasing the resistance of said connection between said source and said terminal to cause actuation of said control relay to cause selection of said line by said switch, and means including said terminal for causing actuation of said first mentioned relay.

2. In a telephone system, a subscriber's line, a plurality of multiply connected test terminals therefor, a relay and a source of current connected with said terminals, a plurality of selector switches each comprising one of said terminals, a control relay for each of said switches, means for decreasing the resistance of said connection between said source and each of said terminals to cause actuation of the control relay of any of said switches to cause selection of said line, means including the test terminal of a selected line to cause actuation of said first mentioned relay and to render the line unselectable by any of said switches.

3. In a telephone system, the combination with a subscriber's line, calling and called test terminals therefor, a relay and a source of current connected with said terminals, a group of selector switches each comprising a calling one of said terminals, a second group of selector switches each comprising a called one of said terminals, of means for increasing the potential of said source at said terminals to render the line selectable by any one of first said switches, and means for reducing the potential of said source at each of said terminals to render said line unselectable by the remaining switches of said groups.

4. In a telephone exchange system, the combination with a subscriber's line, multiply connected calling and called test terminals therefor, a relay and a source of current connected with said terminals, a selector switch adapted to select a calling one of said terminals, a second selector switch adapted to select a called one of said terminals, of means for increasing the potential of said source at said terminals to render the line selectable by the first said switch, means responsive to selection of said line by the first said switch for reducing the potential of said source at said terminals to render the line unselectable by the second said switch, and means responsive to selection of said line effective to cause actuation of said relay.

5. In a telephone system, a subscriber's line comprising a test terminal, a relay and a source of current connected with said terminal, a selector switch, a line relay associated with said subscriber's line, means controlled by said line relay to decrease the resistance of said connection between said source and terminal upon the initiation of a call over said line to cause selection of

said line by said switch, and a circuit including said terminal for causing the actuation of said first-mentioned relay.

6. In a telephone system, a subscriber's line, a plurality of multiply connected test terminals therefor, a relay and a source of current connected with said terminal, a plurality of selector switches each including one of said terminals, a control relay for each of said switches, a line relay associated with said subscriber's line, means controlled by said line relay for decreasing the resistance of said connection between said source

and each of said terminals to cause the actuation of the control relay of any of said switches upon engagement with the terminals of said line to effect selection of said line, and a circuit including the test terminal of a selected line to cause the actuation of said first-mentioned relay to render the line unselectable by any of said switches.

In witness whereof, I hereunto subscribe my name this 28th day of September A. D., 1915.

BERT G. DUNHAM.
